(57) **CLAIM**

The ornamental design for a bottle top basting brush, as shown and described.

DESCRIPTION

FIG. 1 is an isometric view of a bottle top basting brush showing my new design;

FIG. 2 is a front elevational view thereof, the rear and side elevational views being mirror images thereof;

FIG. 3 is a top plan view thereof; and,

FIG. 4 is a bottom view thereof.

The continuous broken line shown in FIG. 4 represents the bounds of the claim. The broken-line boundary and the area within form no part of the claimed design.
